GENERATOR-ABSORBER FOR INTERMITTENT ABSORPTION REFRIGERATORS

Application filed December 12, 1929. Serial No. 413,456.

This invention relates to an improved generator-absorber for refrigeration apparatus of the intermittent absorption class, and to a method of producing heat abstracting fins for, and of applying them to, the generator-absorber, although, as will be clear from the disclosure herein contained, so far as the method and its product are concerned, the invention is not necessarily limited to the class of refrigeration apparatus.

Among the objects of the invention are to provide a generator-absorber for intermittent absorption refrigeration apparatus that is highly efficient both in the transmission of heat to its contents during the heating-condensing period, and in the dissipation of heat therefrom during the cooling-absorption period; that is equally effective in promoting the re-absorption of the refrigerant gas by the solvent during the latter period; that is relatively simple and inexpensive of manufacture; that is amply strong to withstand the high internal pressures to which it is subjected, and that is comparatively light of weight.

Other objects of the invention are to provide a simple and cheap, yet highly efficient, heat-absorbing fin for use on the generator-absorbers of refrigeration apparatus, or on other vessels or containers; and that is particularly convenient of application and attachment to the container or vessel, and that increases the strength of the vessel.

A further object is to provide a method whereby heat-absorbing fins may be simply, economically, and expeditiously produced, applied, and secured to vessels or containers.

Other objects and advantages will appear as I proceed to describe the invention in detail, reference being had to the accompanying drawings wherein Fig. 1 is a central, vertical, longitudinal section through our improved generator-absorber; Fig. 2 is a plan view thereof; Fig. 3 is a transverse, vertical section on the line 3—3 of Fig. 1; Fig. 4 is a diagrammatic representation of a refrigeration apparatus incorporating our improved generator-absorber; Figs. 5 and 6 show, schematically, in side elevation and plan, respectively, apparatus for performing

the first step of producing the heat abstracting fins; Figs. 7 and 8 are similar views showing the second step in the method of producing the fins; Fig. 9 illustrates the step of applying the fins to a shell or vessel that will ultimately form a part of the generator-absorber, and Fig. 10 illustrates the step of securing the fins to the shell or vessel.

The generator-absorber, designated generally by the reference numeral 1, is made up of an upper cylindrical vessel and a lower cylindrical vessel 2 and 3, respectively. For the purpose of description the left hand end of the generator-absorber, as viewed in Figs. 1, 2 and 4, will be considered the front end. The rear, lower portion of the vessel 2 communicates with the corresponding portion of the vessel 3, through a conduit 4 that depends from the upper vessel and passes through the top wall of the lower vessel and terminates a short distance above the bottom wall thereof; and the forward, upper portion of the lower vessel 3 communicates with the adjacent lower portion of the upper vessel 2 through a conduit 5. A deflector 6, in the nature of an inverted trough (see Fig. 3), is inclined upwardly and rearwardly from the top of the conduit 5. The rear portion of the deflector 6 is supported from an adjacent portion of the vessel 2 by a bracket 7. Rising from the top of the vessel, near its rear end, is what we may term a delivery conduit 10, and entering the lower vessel 3 through the rear wall thereof is a conduit 11, which, by reason of its function may be termed the gas return conduit. A roof-shaped deflector 12 leads forwardly and gradually upwardly from the inner end of the gas return conduit 11 well toward the forward end of the vessel 3, and its forward end is supported from an adjacent part of the wall of said vessel by a bracket 13. A drain tube 15, whose purpose will presently appear, leads downwardly through the top of the vessel 2, adjacent the rear end thereof, and through the conduit 4, the lower end of said tube being cut on an angle so that it may rest upon the bottom wall of the vessel 3 without being closed thereby.

Surrounding the vessels 2 and 3 are heat

abstracting fins 16. As will hereinafter more fully appear, these fins collect and transmit heat to the walls and thence to the contents of the vessels during the so-called heating-condensing period of a cycle of operation, and during the subsequent cooling-absorption period they serve to carry the heat away from the contents and walls of the vessels. The method of making and applying these fins constitutes an important part of our invention, as we shall presently explain.

In order that the purpose and advantages of our invention, as it pertains to the generator-absorber, may be better understood, we have shown it diagrammatically in Fig. 4, as embodied in a complete refrigeration apparatus of the intermittent absorption class. The apparatus includes a cooling unit A, located in the top portion of a refrigeration compartment B which, in practice, is enclosed by a suitable insulated cabinet, as will be readily understood, C represents a condenser. A heating device D, which may consist of an oil burning apparatus of approved type, is situated below the generator-absorber 1.

The cooling unit A consists of two double wall vessels *a* which constitute evaporators, and the spaces between the walls of the respective vessels, termed the refrigerant spaces, communicate with each other at the top through a cross tube *a'* and at the bottom through a cross tube *a''*. Situated above the cooling unit is a receiver E from the bottom of which a column *e* descends and joins the cross tube *a''* at about its middle. The cross tube *a'* communicates with the bottom portion of the receiver E through a conduit *a''*.

A suitable distance above the plane of the generator-absorber 1 is a receptacle F. The previously mentioned conduit 10, that rises from the rear portion of the upper vessel 2 of the generator-absorber, extends to an elevation considerably above that of the receptacle F where it turns and descends through the top wall of said receptacle and terminates therein at a point materially below the plane of the upper end of the previously mentioned drain tube 15 that is disposed within said receptacle F, said tube 15 descending through the bottom wall of the receptacle and continuing thence downwardly into the generator-absorber, as above described. A conduit H leads from the top of the receptacle F over and downwardly to where it joins the coil of the condenser C, the lower end of which coil communicates, through a pipe I, with the top of the receiver E.

The beforementioned gas return conduit 11, that enters through the rear wall of the vessel 3, leads from the top of the receiver E. A liquid return tube G has one of its ends disposed within the lower portion of the column *e* adjacent the junction of the latter with the cross tube *a''* of the cooling unit A, while

its adjacent portion passes upwardly through the receiver E and out through the top thereof, the tube continuing upwardly and thence over and downwardly to where its opposite end has communicative connection with the rear of the vessel 3. Communicating with the high part of the liquid return tube is a chamber *g*.

The system comprising the generator-absorber 1, the receptacle F, the coil of the condenser C, the receiver E and the double wall vessels of the cooling unit A, with the tubes, pipes and conduits through which they communicate, is hermetically sealed and contains a suitable refrigerant, such as ammonia, and an absorbent therefor, such as water, in proper proportions. Also, as will be understood, the enclosure surrounding the coil of the condenser C contains a suitable cooling medium, such as water. At the beginning of a cycle of operation all, or substantially all, of the mixture is present in the generator-absorber, although a certain amount may be present within the cooling unit, the absorbent content thereof having been carried over into the cooling unit during the previous heating-condensing period and remaining there after the cooling-absorption period. This part of the mixture remaining in the cooling unit may therefore be referred to as the residue liquid. The level of such liquid in the cooling unit and the level of the mixture in the other parts of the system at the beginning of a cycle of operation, is indicated in Fig. 4 by the dotted lines *y*.

To initiate a cycle of operation, the heating device D is set in action, and the heat rising therefrom causes the mixture within the generator-absorber to boil. The resultant vapors pass through the conduit 10 and, bubbling up through the liquid in the receptacle F, continue on through the conduit H to the coil of the condenser. All, or the greater percentage of absorbent vapors that are carried off with those of the refrigerant are condensed before they reach the highest part of the conduit H and flow back into the receptacle F to join the body of liquid in said receptacle, which, being thus enlarged, overflows through the drain tube 15 back into the generator-absorber.

Assuming that the temperature of the cooling water or agent in the condenser C is low enough to cause condensation of the refrigerant vapors at the pressure then prevailing in the system, said vapors will condense and gravitate through the pipe I to the receiver E and thence through the tube *a''* and cross tube *a'* to the refrigerant spaces of the double wall vessels or evaporators, *a*.

It must be explained, however, that at the beginning of the heating-condensing period the pressure in the system rises very rapidly and as a result thereof, the mixture in the generator-absorber, and the residue liquid

in the cooling unit, are depressed, which causes the mixture and said liquid to rise within the respective ends of the liquid return tube J, the gas trapped between the 5 opposed columns of liquid being compressed in the chamber g. Also, said gas, being rich in refrigerant, is absorbed to a certain extent by the mixture and the residue liquid, and by a combination of these conditions 10 the two columns of liquid are caused to very closely approach each other or actually join so as to effect a continuous or approximately continuous body of liquid throughout the length of the liquid return tube, and inasmuch as the branch of said tube which joins the generator-absorber is longer than the other a siphonic action is set up which draws all or practically all of the residue liquid 15 from the cooling unit over into the generator-absorber thus emptying said unit and preparing it for the subsequent charge of relatively pure anhydrous refrigerant, delivered thereto as above explained. Here it may be well to point out that the relatively pure anhydrous refrigerant will not siphon because when it reaches the part of the liquid return tube G that is exposed to the atmospheric temperature it flashes into gas and breaks the siphon. Therefore the cooling unit will 20 not be robbed of any of its active agent.

By the end of the heating-condensing period the liquid levels in the various parts of the system have changed to those indicated by the dotted lines z in Fig. 4.

35 The heating-condensing period ceases and the cooling-absorption period begins when the application of heat to the generator-absorber is discontinued, as by the rendering of the heating device D ineffective. When this occurs the pressure in the system starts to fall and, under the reduced pressure and the influence of the temperature of the refrigeration compartment B, the refrigerant in the evaporators or vessels a begins to vaporize 40 and the resultant gas returns through the conduit 11 to the lower vessel 3 of the generator-absorber for re-absorption by the relatively weak mixture therein. The incoming gas tends to flow along the underside of 45 the deflector 12 toward the forward end of the vessel 3 where it rises through the conduit 5 into the upper vessel 2. This creates a circulation of the mixture upwardly through the conduit 5, longitudinally of the vessel 1, downwardly through the conduit 4 to the bottom of the lower vessel 3 and thence lengthwise thereof, etc., effecting a thorough intermingling of the refrigerant and the absorber.

50 The method by which the heat abstracting fins are produced, applied and secured to the shells whereof the vessels of the generator-absorber are constructed will now be described.

55 A strip or ribbon 16^a of suitable heat con-

ducting material, such as steel of the desired grade and thickness, is advanced through a series of forming rolls, indicated at 20, 21, and 22, in Figs. 5 and 6, which progressively act upon the strip or ribbon to form it into a channel 16^b that is then passed through a sizing die 23. The channel thus formed is next acted upon by a cylindrical roller 25 (Figs. 7 and 8) and two groove rollers 26 and 27 to impart to it a helical form having an internal diameter approximately the same as the external diameter of the shell or vessel to which it is to be applied. The rollers 26 and 27 confine the side flanges of the channel against lateral distortion while the web of the channel is being formed to the contour of a cylinder.

As indicated in Fig. 9, the helical channel is next slipped endwise over the shell or vessel designated 30, until its advancing end is near the inner end of the latter when the assembly is subjected to the action of welding apparatus, illustrated diagrammatically in Fig. 10, and consisting of opposed electrodes 31 and 32, shown as wheels or rollers, that constitute the terminals of an electric circuit represented by the conductors 33 and 34. The outer wheel or roller is of a thickness to comfortably enter the channel 16^a, and the welding process employed is preferably that known as stitch welding, effected by frequent current interruptions. The result, however, is an uninterrupted weld between the channel and the vessel. The convolutions of the helix are properly spaced from one another during the welding operation by suitable gauge means designated 35.

55 In the construction of the vessels 2 and 3 of the generator-absorber from shells to which the heat abstracting fins have been secured, the openings for the various conduits that pass through the vessels are made in the walls of the shells after such parts of the fins are cut away as would interfere with the operation. The conduits 4 and 5 are then secured in place in the shells, together with the entering portion of the conduit 11, and the baffles 6 and 12 are secured to the respective conduits 5 and 11 and are braced from the shells by means of the brackets 7 and 13. The opposed shells which form the opposite ends of the respective vessels 2 and 3 are presented to each other in axial alignment with their open ends abutting and the shells are then welded together. In practice there is sufficient space left between the end of each shell and the adjacent end of the channel 16^b to enable the shells to be conveniently welded together, and after the weld has been completed a section of channel is fitted about the equator of the vessel in order to join the opposed helices and thus render the channel member which forms the heat abstracting fins 16 substantially continuous from end to end of the vessel. It is evident that the channel members

impart considerable strength to the cylindrical walls of the vessels 2 and 3 and allow lighter metal to be used for such vessels than would otherwise be permitted.

5 Having thus described our invention, what we claim is:

1. A generator-absorber for intermittent absorption refrigeration apparatus comprising a structure enclosing an upper chamber 10 and a lower chamber, means through which the top portion of the lower chamber communicates with the bottom portion of the upper chamber, means spaced therefrom through which the lower portion of the upper 15 chamber communicates with the bottom portion of the lower chamber, and means within the upper chamber for directing the flow of liquid from the first mentioned communicating means toward the second mentioned communicating means, the upper chamber having a vapor outlet and the lower chamber a gas inlet.

2. A generator-absorber for intermittent absorption refrigeration apparatus comprising a structure enclosing an upper chamber 25 and a lower chamber, means through which the top portion of the lower chamber communicates with the bottom portion of the upper chamber, and means spaced therefrom through which the lower portion of the upper chamber communicates with the bottom portion of the lower chamber, the upper chamber having a vapor outlet and the lower chamber a gas inlet, and an inverted trough-like extension leading from the gas inlet longitudinally of the lower chamber for preventing immediate rise of gas issuing from the inlet.

3. A generator-absorber for intermittent absorption refrigeration apparatus comprising a structure enclosing an upper chamber 40 and a lower chamber, means through which the top portion of the lower chamber communicates with the bottom portion of the upper chamber, means spaced therefrom through which the lower portion of the upper chamber communicates with the bottom portion of the lower chamber, the upper chamber having a vapor outlet and the lower chamber a gas inlet, and means within the lower chamber 45 for preventing immediate rise of gas issuing from the inlet and for directing said gas toward the first-mentioned communicating means.

4. A generator-absorber for intermittent absorption refrigeration apparatus comprising an upper elongated vessel, a lower elongated vessel, a conduit through which the top portion of one end of the lower vessel communicates with the lower portion of the corresponding end of the upper vessel, a second conduit through which the lower portion of the opposite end of the upper vessel communicates with the bottom portion of the corresponding end of the lower vessel, the upper 65 vessel having a vapor outlet and the lower

vessel having a gas inlet, and a baffle in the upper vessel extending from the upper end of the first-mentioned conduit gradually upwardly toward the opposite end of said upper vessel.

5. A generator-absorber for intermittent absorption refrigeration apparatus comprising an upper elongated vessel, a lower elongated vessel, a conduit through which the top portion of one end of the lower vessel communicates with the bottom portion of the corresponding end of the upper vessel, a second conduit through which the bottom portion of the opposite end of the upper vessel communicates with the bottom portion of the corresponding end of the lower vessel, a gas return conduit entering the last mentioned end of the lower vessel, and a baffle extending from the top side of the discharge end of said gas return conduit gradually upwardly therefrom toward the opposite end of said lower vessel, the upper vessel having a vapor outlet.

6. A generator-absorber for intermittent absorption refrigeration apparatus comprising an upper elongated vessel, a lower elongated vessel, a conduit through which the top portion of one end of the lower vessel communicates with the bottom portion of the corresponding end of the upper vessel, a second conduit depending from the bottom wall of the opposite end of the upper vessel through the top wall of the lower vessel and terminating adjacent the bottom wall of the latter vessel, and a drain tube extending downwardly through the top wall of the upper vessel and through the second-mentioned conduit and terminating adjacent the bottom thereof, the upper vessel having a vapor outlet and the lower vessel a gas inlet.

7. A generator-absorber for intermittent absorption refrigeration apparatus comprising a structure enclosing an upper chamber and a lower chamber, means through which the top portion of the lower chamber communicates with the bottom portion of the upper chamber, a conduit spaced from said means and depending from the upper chamber into the lower chamber and terminating adjacent the bottom wall of the latter chamber, and a drain tube extending downwardly through the top wall of the upper chamber and through said conduit and terminating adjacent the bottom thereof, the upper chamber having a vapor outlet and the lower chamber a gas inlet.

8. A generator-absorber for intermittent absorption refrigeration apparatus comprising two substantially parallel and horizontal cylinders arranged one above the plane of the other, the opposite ends of the cylinders communicating, the lower cylinder being completely filled and the upper cylinder partly filled with liquid, and a flow directing instrumentality for promoting a circulation of the liquid between the two cylinders.

9. A generator-absorber for intermittent absorption refrigeration apparatus comprising two substantially parallel and horizontal cylinders, one being at a higher elevation than the other, the opposite ends of the cylinders communicating, the lower cylinder being completely filled and the upper cylinder partly filled with liquid, a gas inlet entering the lower cylinder, and an instrumentality for directing the flow of gas so as to produce a circulation of the liquid between the two cylinders.
10. In combination, a generator-absorber for intermittent absorption refrigeration apparatus comprising two substantially parallel and horizontal cylinders, one being at a higher elevation than the other, the opposite ends of the cylinders communicating, the lower cylinder being completely filled and the upper cylinder partly filled with liquid, means for applying heat underneath the lower cylinder and reversely inclined baffles, one in each cylinder, whereby the application of heat produces a circulation of liquid between the two cylinders.
11. In combination, a generator-absorber for intermittent absorption refrigeration apparatus comprising two substantially parallel and horizontal communicating cylinders, one being at a higher elevation than the other, the lower cylinder being completely filled and the upper cylinder partly filled with liquid, the first mentioned cylinder having a gas inlet and the second mentioned cylinder a gas outlet, means for alternately heating and cooling the generator-absorber, and an instrumentality serving to direct the flow of gas so that a circulation of the liquid between the two cylinders takes place during both the heating and cooling periods.
40. In testimony whereof, we hereunto affix our signatures.
